UNITED STATES PATENT OFFICE.

HARRY SCHANDEIN AND MONROE P. LIND, OF PHILADELPHIA, PENNSYLVANIA.

DISPLAY-BOX.

1,030,209.

Specification of Letters Patent.

Patented June 18, 1912.

Application filed November 25, 1911. Serial No. 662,405.

To all whom it may concern:

Be it known that we, HARRY SCHANDEIN and MONROE P. LIND, citizens of the United States, residing at Philadelphia, in the county of Philadelphia and State of Pennsylvania, have invented certain new and useful Improvements in Display-Boxes, of which the following is a specification.

This invention relates to display boxes, and especially to the class of terraced boxes for displaying articles of merchandise such as individual boxes or packages of perfumed confections, perfumery, etc., and the particular object of this invention is to provide a partition for separating the tiers of individual boxes held by the terraced supports, and to provide the partitions with means for holding them perpendicular to the terraced supports.

20 The invention is specially applicable to the box patented to us July 19, 1910, No. 965,019, which we have found susceptible of the improvement forming the subject matter of this application, and by means of which 25 this invention is carried out.

In the accompanying drawings forming part of this application:—Figure 1 is a perspective view of the box partially filled and showing certain of the partition braces extended. Fig. 2 is a cross section of the terraced supports, the dotted lines showing the partition braces extended. Fig. 3 is a plan view of a partition blank. Fig. 4 is a perspective view of a partition partly broken 35 away showing the braces in two positions.

The same reference characters denote the same parts throughout the several views of the drawings.

The construction of the display box for 40 which this invention is specially designed is covered by our patent hereinbefore mentioned, therefore said box will not be described in detail, but will only be herein referred to in so far as necessary for this application.

The display box 1, and its attachments, are preferably made of cardboard, or similar material, capable of being bent and folded, and the box has a closed back 2, 50 provided with a covering flat 3, closed ends 4, a bottom 5, and a stiffened front flange 6. The box is divided lengthwise into a series of article-holding pockets 7, by means of steps or terraced supports 8 extending from 55 one to the other of the box ends, and a longitudinal pocket 9 is formed adjacent to the

front flange 6. The steps or supports 8 each has a portion 10, projecting above it which forms a front for the pocket 7.

For the purpose of convenience in vending and protecting the individual boxes, it has been found desirable to separate (longitudinally) the articles or individual confection boxes 11, contained in each pocket, and for this, among other purposes, a longitudinal partition 12 is placed in each pocket. It has also been found that in vending the boxes 11, the boxes remaining in the broken tiers tilt or fall forward by reason of the depth and flexibility of the partitions 12, 70 and for the purpose of overcoming this disadvantage and objection, the partitions are made with braces 13. The partitions 12, all being of the same design or construction, only one of them will be described in detail, 75 it is composed of foldable or flexible material such as cardboard, adapted to be bent longitudinally at right angles on the dotted line A—A (Fig. 3) so as to form a base 14, and a partition portion 15, said base being 80 attached to the supports 8, and in the pocket 9. The portion 15, has the braces 13 partially cut out of it, and such braces are projected at right angles to the portion 15 by bending them outwardly on the dotted lines 85 B. The braces 13 of the respective partitions are of such length as to engage the box-front flange 6 and the pocket fronts 10, and thereby hold the partitions in upright or vertical position when the pockets are 90 not fully occupied. When the pockets are fully occupied the braces are not used but they remain flush with the partitions and do not interfere with the individual boxes. In displaying (in a single tier for each pocket) 95 articles of greater size or thickness than the individual boxes, the partition portion 15 is not bent into vertical position but may remain in flat position.

It will be observed that the individual boxes are arranged in two tiers for each pocket or terrace, with the partitions dividing or separating the tiers of each terrace; that the partitions and one or more of the partition braces may be used according to 105 the number of individual boxes on display; and that, in the event of any one of the front tiers of boxes being displaced, the boxes of the next or rear tier will be displayed in proper position by bending the 110 braces outwardly into engagement with the adjacent front or fronts of the pockets,

We do not wish to be understood as confining ourselves in the size, material or application of the partitions, nor to the manner, size or shape of the partition braces; but 5 reserve to ourselves the right to vary the application, size, shape and number of the partitions and the braces as may be found desirable or necessary, without departing from the spirit of the invention as set up in the 10 appended claims.

Having thus described our invention what we claim as new and desire to secure by Letters Patent is:—

1. The combination, with a box having 15 terraced pockets for displaying articles of merchandise therein, of means for forming an inner bottom for the pockets and for converting each pocket into a pair of pockets, comprising a flexible section, one portion 20 thereof being secured and the other portion being bendable from flat position to vertical position, and a plurality of braces partially cut out of the said bendable portion and adapted to be projected therefrom into en-

gagement with the pocket fronts for bracing the said bendable portion in vertical position. 25

2. The combination, with a display box having terraced pockets, of a partition having a portion secured to and covering part 30 of the bottom of the pockets, and a bendable portion free from and covering the other part of the pocket bottoms and adapted to stand at right angles to said bottoms for longitudinally dividing each of said pockets 35 into two pockets, and a plurality of braces struck out of and foldable flush with said bendable portion and adapted to have free engagement with the pocket fronts for holding the bendable portion in vertical position. 40

In witness whereof we hereunto set our hands in the presence of two witnesses.

HARRY SCHANDEIN.
MONROE P. LIND.
